(57) **CLAIM**

The ornamental design for a lighter attachment, as shown and described.

DESCRIPTION

FIG. 1 is a top front perspective view of a lighter attachment; FIG. 2 is a front elevation view thereof; FIG. 3 is a rear elevation view thereof; FIG. 4 is a right side elevation view thereof, the left side elevation view being a mirror image thereof; FIG. 5 is a top elevation view thereof; FIG. 6 is a bottom elevation view thereof; and, FIG. 7 is a top front perspective view thereof, shown in use. The broken lines shown in the drawings depict portions of the lighter attachment and environmental lighter that form no part of the claimed invention.
